(57) **CLAIM**

The ornamental design of an offset display holder, as shown and described.

DESCRIPTION

FIG. 1 is a perspective view taken from the front, top, right side of the offset display holder showing my new design; FIG. 2 is a top plan view of the offset display holder of FIG. 1;

FIG. 3 is a bottom plan view of the offset display holder of FIG. 1;

FIG. 4 is a front elevational view of the offset display holder of FIG. 1;

FIG. 5 is a back elevational view of the offset display holder of FIG. 1; and

FIG. 6 is a right side elevational view of the offset display holder of FIG. 1; [and,]

FIG. 7 is a left side elevational view of the offset display holder of FIG. 1[.];

FIG. 8 is a perspective view taken from the front, top, right side of the offset display holder showing a second embodiment of my new design;

FIG. 9 is a top plan view of the offset display holder of FIG. 8;

FIG. 10 is a bottom plan view of the offset display holder of FIG. 8;

FIG. 11 is a front elevational view of the offset display holder of FIG. 8;

FIG. 12 is a back elevational view of the offset display holder of FIG. 8;

FIG. 13 a right side elevational view of the offset display holder of FIG. 8;

FIG. 14 is a left side elevational view of the offset display holder of FIG. 8; and,

FIG. 15 is an enlarged view of FIG. 13.

Portions shown in broken lines depict environmental subject matter only and form no part of the claimed design.

1 Claim, 6 Drawing Sheets

Matter enclosed in heavy brackets [ ] appears in the original patent but forms no part of this reissue; matter printed in italics indicates the additions made by reissue.
